UNITED STATES PATENT OFFICE

ROY E. PETERSON, OF NORWALK, CONNECTICUT, ASSIGNOR TO THE E. H. HOTCHKISS COMPANY, OF NORWALK, CONNECTICUT, A CORPORATION OF CONNECTICUT

DESK STAPLING MACHINE

Application filed February 9, 1929. Serial No. 338,803.

This invention relates to stapling machines and has for an object to provide improved means for setting staples so that the prongs will lie flat on the surface of the work and will be closely clinched so as to better hold the work and not project an undesirable extent above the surface thereof.

With the foregoing and other objects in view, the invention consists in certain novel features of construction, combinations and arrangements of parts as will be more fully disclosed in connection with the accompanying drawings. In the drawings,

Fig. 1 is a partial side elevation and partial section showing a stapling machine having my improved clinching means.

Fig. 2 is a vertical section substantially on line 2—2 of Fig. 1 and on a larger scale.

Fig. 3 is a similar view showing the parts in position of clinching the staple.

Fig. 4 is a side elevation of one of the clinching anvils, and

Fig. 5 is an edge view thereof.

The machine illustrated comprises the usual base 10 to which is pivoted the housing 11 at 12. The housing carries the usual vertically reciprocating plunger 13 which may be of the type disclosed in the patent to Polzer, #1,588,990, June 15, 1926, operated by a knob 12 at its upper end by a blow from the hand, and is normally held in its upper position by a spring 15 either outside or within the housing as desired. The staples 16 which are substantially U-shape are preferably of wire either round or somewhat flattened and are fed in an inverted position with their prongs downwardly along the top of the guide bar 17 by means of an inverted U-shaped follower 18 drawn forward by a spring 19 to feed the staples successively to the position for driving under the plunger.

The base 10 carries a block 20 having a transverse slot in which are mounted the clinching anvils 21. There are two of these anvils pivoted on transverse pins 22 and their free ends 23 extend toward each other and the upper edges thereof are inclined downwardly, as shown in Fig. 2, when the parts are in the normal position of rest. These upper edges are preferably provided with longitudi-

nal grooves 24 to receive and guide the prongs 25 of the staples. On the opposite sides of the pivots 22 from the free ends 23 the anvils are provided with curved cam lugs 26 normally projecting somewhat above the top surface of the block 20. The anvils also have downwardly projecting arms 27 carrying lugs 28 for supporting the opposite ends of a coil spring 29. This spring tends to spread the arms 27 and retain the elements in the position of Fig. 2. The walls 30 of the base at the opposite ends of the slot act as stops to limit the outward movements of these arms.

In operation the articles to be stapled, such as the sheets of paper 31, are placed on top of the cam lugs 26 and under the forward end of the housing after raising the housing. The forward end of the housing then rests on top of the paper and when the plunger is depressed by a blow on the knob 14 the prongs 25 of the staple 16 are forced through the sheets of paper and their ends engage slots 24 on the top edges of the anvils 21, and as these edges are inclined downwardly and inwardly the prongs are bent inwardly somewhat, as shown in Fig. 2. Further movement of the plunger and hand knob 14 downwardly carry with them the forward end of the housing 11 as downward movement of the plunger relative to the housing is limited by suitable stop means, for example by the shoulder 33 on the plunger engaging the stop 34, and as the under surface 32 of the housing rests on the cam lugs 26 this movement will press these lugs downwardly and will turn the anvils to the position of Fig. 3, forcing the free ends 23 against the under sides of the work 31. This movement of the anvils will also carry with them the prongs of the staples and will tightly press them against the under side of the work, and furthermore, will lay them out straight; as shown in Fig. 3. The prongs are, therefore, not curved so as to project an undesirable amount above the surface of the work as is the case where a stationary anvil using curved clinching surfaces is employed.

It will be seen that this movement of the anvil will give a positive folding or bending action to the prongs of the staples, very securely clinching them and giving a flat staple pro-

jecting the minimum amount above the surface of the work.

Having thus set forth the nature of my invention, what I claim is:

5. 1. In a stapling machine, a base, a housing pivoted to the base, a movable plunger in the housing, means for operating the plunger, one or more movable anvils mounted in the base to cooperate with said plunger to set a staple, 10 said housing being normally spaced from the base, and said anvil or anvils including means adapted to cooperate with the housing by relative movement of the housing and base to shift the anvil or anvils toward the plunger.
15. 2. In a stapling machine, a base, a housing pivoted to the base, a movable plunger in the housing, means for operating the plunger, a pair of anvils pivoted to the base below the plunger and adapted to cooperate with the plunger in setting a staple, and said anvils including means adapted to cooperate with the housing by relative movement of the housing and base to swing the anvils toward the plunger.
20. 3. In a stapling machine, a base, a housing pivoted to the base, a movable plunger in the housing, means for operating the plunger, a pair of anvils pivoted in the base below the plunger and adapted to cooperate therewith to set a staple, lugs on the anvils to normally hold the housing above the base and adapted to cooperate with the housing to swing the anvils toward the plunger on movement of the housing toward the base, and resilient 25 means tending to hold the anvils in the retracted position.
25. 4. In a stapling machine, a base, a housing pivoted to the base, a movable plunger in the housing, means for operating the plunger, a pair of anvils pivoted to the base below the plunger and having lugs engaging the under side of the housing to normally hold it spaced above the base, and a spring tending to hold the anvils in this position, said lugs being adapted to cooperate with the housing to swing the anvils toward the plunger on movement of the housing toward the base.
30. 5. In a stapling machine, a base, a housing pivoted to the base, a movable plunger in the housing, means for operating the plunger, said base being provided with a transverse slot under the plunger, a pair of anvils pivoted in said slot and having free ends movable toward the plunger, lugs on the opposite sides of the pivots from the free ends normally engaging the under side of the housing, arms on the anvils, a spring between the arms tending to separate them and hold the lugs against the housing, and stop means 35 to limit turning movements of the anvils under action of the spring.
35. 6. In a stapling machine, a base, a housing pivoted to the base, a movable plunger in the housing, means for operating the plunger, a pair of anvils pivoted in the base below

the plunger to cooperate therewith to set a staple, and lugs on the anvils adapted to cooperate with the housing to swing the anvils toward the plunger on movement of the housing toward the base.

7. In a stapling machine, a base, a housing pivoted to the base, a movable plunger in the housing, means for operating the plunger, a pair of anvils pivoted in the base below the plunger to cooperate therewith to set a staple, lugs on the anvils adapted to cooperate with the housing to swing the anvils toward the plunger on movement of the housing toward the base, and resilient means tending to hold the anvils in retracted position.

8. In a stapling machine, a base, a housing pivoted to the base, a movable plunger in the housing, means for operating the plunger, an anvil pivoted in the base below the plunger to cooperate therewith in setting a staple, and said anvil including means adapted to cooperate with the housing to swing the anvil toward the plunger on movement of the housing toward the base.

9. In a stapling machine, a base, a housing pivoted to the base, a movable plunger in the housing, means for operating the plunger, an anvil pivoted in the base below the plunger and adapted to cooperate therewith in setting a staple, and a lug on the anvil adapted to cooperate with the housing to swing the anvil toward the plunger on movement of the housing toward the base.

In testimony whereof I affix my signature.

ROY E. PETERSON.
